CULINARY MIXING BOWL OR SIMILAR ARTICLE

Charles O. Bliss, Los Angeles, Calif.

Application April 21, 1954, Serial No. 30,110

Term of patent 14 years

(Cl. D44—1)

FIG. 2

FIG. 3

FIG. 4

FIG. 1

Fig. 1 is a perspective view of a culinary mixing bowl showing my new design;

Fig. 2 is a view of the top of the bowl, on a somewhat smaller scale;

Fig. 3 is a bottom plan view of the bowl; and

Fig. 4 is a side view thereof.

I claim:

The ornamental design for a culinary mixing bowl or similar article, substantially as shown.
